UNITED STATES PATENT OFFICE.

EDWARD WILSON, OF ST. LOUIS, MISSOURI, ASSIGNOR TO NATIONAL PUMP AND COMPRESSOR COMPANY, OF ST. LOUIS, MISSOURI, A CORPORATION OF DELAWARE.

PISTON BLADE.

Application filed December 26, 1925. Serial No. 77,687.

My invention relates to improvements in piston blades, and has for its primary object a piston blade which is designed for use in rotary compressors or rotary vacuum pumps and is constructed with a rocking shoe which is designed for constant contact with the interior of the cylinder in which the rotor carrying the blade rotates.

A further object is to construct a piston blade of two separate unattached members, which carry on their outer edge a rocking shoe, the shoe adapted to rock during the movement or sweep of the piston blade through a cylinder and by so rocking to maintain at all times a relatively wide surface in contact with the interior of the cylinder.

A still further object is to construct a piston blade having a substantially T shaped shoe which is carried by two complementary flat members, these members being capable of independent lateral movement so that the upper edges of the member will always be in contact with the shoulders or underside of the head of the shoe thereby maintaining an airtight connection between the shoe and the individual members of the blade.

In the drawings:

Fig. 1 is a face view of my improved blade with the shoe in position;

Fig. 2 is a vertical section taken on the line 2—2 of Fig. 1;

Fig. 3 is an end view of my blade with the shoe removed;

Fig. 4 is an inside face view of one of the sections;

Fig. 5 is an end view of the shoe;

Fig. 6 is a fragmental view showing a portion of the rotor and cylinder with my blade in position and just ready to commence sweeping through the compression chamber;

Fig. 7 is a similar view showing the position of the various parts of the blade when a quarter revolution has been made;

Fig. 8 is a similar view when a half revolution has been completed;

Fig. 9 is a similar view when three-quarters of a revolution has been made; and

Fig. 10 is a view of my blade illustrating the movement of the blade sections and rocking shoe and showing how the air-tight joint is maintained between the shoulders of

the shoe and the upper edges of the blade. 55

In the construction of my device I employ a piston blade composed of complementary plates 11 and 12. The plate 11 is provided with ribs 13 and 14 and the plate 12 with ribs 15 and 16. These ribs are designed to abut as illustrated in Figs. 2 and 3 thus forming a pressure space or pocket 17. The ribs 13 and 16 are adjacent one of the longitudinal edges of the plates while the ribs 14 and 15 are positioned at some 60 distance below the edges 18 and 19 of the plates 11 and 12 respectively so as to form a channel or groove 20. The walls of this channel or groove are preferably tapered as 65 illustrated in Figs. 2 and 3. The shoe, which is located in this channel or groove, is substantially T shaped having a head 21. The upper face 22 of this head is curved so that it will bear snugly against the interior 70 of the compression cylinder. Therefore, 75 the curvature of this face will be varied with various faces of cylinders.

Extending downwardly and at an angle to the vertical are the longitudinal faces 23, along the lower edge of which are formed shoulders 24 and 25. Below the shoulders is a extension 26 which has curved longitudinal walls 27 and 28. These walls are curved on the arc of a circle having as its center a point midway the width of the 85 shoulder 24 while the wall 27 is curved similarly but has the center of its curve taken on the shoulder 25. These curved walls form a rolling contact with the walls 90 of the channel or groove so as to eliminate wear at these points. One of the plates either 11 or 12 has secured thereto resilient or spring members 29, the free ends of which contact with the opposite plate. The purpose of this is to have the plates spread 95 apart so that they will fit snugly against the walls of the piston blade pocket which is formed in the rotor.

My piston blade may be operated either mechanically or by centrifugal force, and by 100 operation is meant the holding of the shoe against the interior face of the compression cylinder and the sections of the blade against the shoulders 25 and 24. It will be noted from Figs. 7 and 9 that in order to 105 maintain a tight joint and a full contact between the shoe and the interior of the cylinder, the shoe must rock and in so doing

one of the shoulders will have a tendency to raise or draw away from the upper edge of one of the plates. When this occurs centrifugal force will move that section of the 5 blade outward and maintain a tight joint. It is, of course, to be understood that my device is used in compressors where the rotor is mounted eccentrically to the compression cylinder. This is clearly illustrated in 10 Figs. 6, 7, 8 and 9 in which also a mechanical means for moving and maintaining the piston against the cylinder head is shown by dotted lines.

During the operation of my device, there 15

will always be more or less oil fed to the compression chamber, which will be distributed over the piston and this oil gets in between the shoulders 25 and 24 and the edges 18 and 19 will form an oil seal and assist in making the joint air-tight. The oil 20

will also get on the faces of the ribs and the free ends of the resilient members 29 thus permitting the plates to slide on each other and assume the position shown in Fig. 10.

25 While I have shown my device as employing a leaf spring, it is obvious that other means may be used, which have a normal tendency to force the plates apart or these parts may be omitted entirely as there will 30 always be sufficient amount of gas pressure between the plates entering through the ports 30 to hold them apart when the device is in operation. These ports may be either openings drilled through the ribs or may be 35 made by cutting notches of any desired shape in the vertical edges of the ribs. It is also an essential feature of my device that the length of the shoe and the length of the plates be exactly the same so that there can 40 be no leakage past the piston from the compression chamber into the suction chamber.

Having fully described my invention, what I claim is:

45 1. A piston blade composed of complementary sections slidably arranged against each other so as to form a groove in the outer edge of said blade, and a shoe of the same length as the blade located in said groove, said shoe capable of being rocked by the relative outward movement of said sections.

50 2. A piston blade composed of complementary sections slidably arranged against each other so as to form a channel in the outer edge of said blade, a shoe of the same length as the blade located in said channel, said shoe capable of being rocked by the

relative outward movement of said sections, and means interposed between said sections for normally forcing them apart. 60

3. A piston blade composed of complementary sections slidably arranged against each other so as to form a groove in the outer edge of said plate, a shoe located in said groove, said shoe capable of being rocked by the relative outward movement of said sections, and a spring interposed between said sections. 65

4. A piston blade composed of two sections arranged face to face and capable of 70 being moved relative to each other, a groove formed in the outer edge of said blade, a shoe mounted in said groove, shoulders formed on the opposite face of said shoe intermediate its edges and adapted to engage 75 with the outer edges of the sections whereby the shoe may be rocked by the relative movement of the sections and an air-tight connection is formed and maintained between said shoulders and the edges of the sections. 80

5. A piston blade composed of complementary sections provided with pockets on their inner surfaces, said sections slidably arranged against each other so as to form a groove in the outer edge of said blade, a 85 shoe of the same length as the blade located in said groove and adapted to rock therein by the relative movement of the sections, and a leaf spring mounted in one of said pockets and projecting into the other pocket 90 for normally forcing the sections apart.

6. A piston blade composed of sections provided with ribs on their inner faces and slidably arranged against each other so as to form a groove in the outer edge of said 95 blade, each of the sections being provided with pockets on the inside face between the ribs, said blade being provided with a groove or recess in its outer edge, and a shoe of the same length as the blade located in said 100 groove and capable of being rocked by the relative outward movement of said sections.

7. A piston blade composed of complementary sections provided with a pressure pocket on the inside faces thereof, said sections being slidably arranged and provided with a channel in their outer edges, a shoe of the same length as the blade located in said channel, said shoe capable of being rocked by the relative outward movement of said 105 sections. 110

In testimony whereof I have affixed my signature.

EDWARD WILSON.
